UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

KNIFE-LUBRICATING DEVICE.

1,080,485.

Specification of Letters Patent.

Patented Dec. 2, 1913.

Application filed January 2, 1906. Serial No. 294,256.

To all whom it may concern:

Be it known that I, DUDLEY S. SEYMOUR, a citizen of the United States, residing at Oak Park, in the county of Cook, State of Illinois, have invented certain new and useful Improvements in Knife-Lubricating Devices, of which the following is a description, reference being had to the accompanying drawing and to the letters and figures of reference marked thereon.

This invention relates to sewing machines, of that class in which bags, curtains and other articles are united by a continuous chain of stitching which is severed after the sewing of each article. In this type of machine, the cutting blades are exposed to considerable frictional wear, and this is enhanced by accumulations from the articles being stitched, and from clippings of the thread. In many cases the fabric is sized, filled or painted, and this material becomes detached by the needle during the sewing operation and acts to absorb any oil on the knives and clog the same.

The principal object of the present invention is to improve the operation and lengthen the life of the knives by providing for their proper lubrication during the entire operation.

A further object of the invention is to provide a lubricator of simple construction and to so arrange the same that the blades will be constantly supplied with oil.

With these and other objects in view, the invention consists in the construction and combination of elements hereinafter described, illustrated in the drawings, and particularly pointed out in the claims.

Figure 1 is a sectional elevation of a portion of a sewing machine provided with a knife lubricator constructed in accordance with the invention. Fig. 2 is a plan view of a portion of the machine showing the cutting blades and their lubricating device. Fig. 3 is a sectional end view. Fig. 4 is a detail perspective view of the several parts of the lubricator detached. Fig. 5 is an end view of the lower part of Fig. 1.

Similar numerals of reference indicate like parts throughout the several figures.

The sewing machine to which the present invention is applied is intended principally for the sewing of bags, or other articles, and its construction and operation are specifically described in an application for Let-

ters Patent, filed by me January 2, 1906, Serial No. 294,256. It will be understood however, that in this case the machine shown is merely typical, and that the invention is not in any sense limited to the sewing or to the precise cutting mechanism shown, but may be employed in connection with any machine in which a movable knife is used for any purpose.

In the machine shown in the present instance, the articles to be sewed are fed consecutively under the presser foot A, while the stitch forming operation is continuous, so that a short length of free chain is left between the successive articles. As each article passes to the rear of the stitching mechanism, an automatic device engages the chain and forces it down between two knives, 60 and 64, the knife 64 moving relatively to the knife 60 and severing the chain. The knife 60 is firmly secured within a slot 60', that is formed in one of the end bearings of the main shaft C and its vertical cutting edge is arranged in alignment with one wall of the throat plate slot, through which the chain is depressed, the chain being supported by an extended finger 60' of the knife.

On the lower portion of the bed plate is secured a block 61 forming a bearing for a transversely disposed shaft 62, to which is secured a rocker arm 63. The upper end of the rocker arm is grooved for the reception of the movable cutting knife 64. A rocker arm 65 is provided on the shaft 62, having thereon a ball fitting a socket in the connecting rod 66. At the other end of the connecting rod is an eccentric strap 67, surrounding an eccentric on the main shaft C of the machine.

The movable knife is in constant frictional contact with the stationary knife so long as the shaft C rotates and this friction enhanced by clippings, filling, paint and the like, results in considerable wear. In order to lessen this wear, an absorbent pad a, generally formed of an L-shaped piece of felt is placed against the face of the stationary knife 60 and is held in place by a clamping plate b, having a rearwardly projecting tongue c, to follow the lower portion of the pad and the finger 60' of the knife. The clamping plate enters the same slot as the stationary knife and the two are held in place by a suitable set screw or equivalent locking means.

The pad is saturated with oil which may be supplied in any well known way. The pad is so arranged that the movable knife engages with the edge thereof at each movement and draws away sufficient oil to keep the knives properly lubricated, the distribution of the oil being assisted by the rapid operation of the movable knife which, at each out stroke, will tend to throw the film of oil upward and thus cover the entire surface exposed to friction. It will be apparent that this pad is in contact at times with a portion of the movable knife. This automatic lubrication is found to materially lengthen the lives of the knives and materially improves the running of the machine.

Having thus described my invention, what I claim and desire to secure by Letters Patent, is—

- 20 1. A movable knife, a fixed knife, and a lubricant saturated pad held against the fixed knife and in contact also with a portion of the movable knife.
- 25 2. In combination, a fixed knife, a lubricant saturated pad, a clamp for holding the pad against the knife, and a movable knife coacting with said fixed knife.
3. In combination, a fixed knife having a

finger projecting beyond its cutting edge, an L-shaped pad, a clamp for holding the pad against the knife, and a movable knife coacting with the fixed knife.

4. In combination, a pair of cutting knives, one of which is movable with respect to the other, one of said knives having a projecting finger in constant engagement with the other knife and maintaining said knives in proper relative position, and a lubricant saturated pad held in contact with a portion of the movable knife and also held against the other knife.

5. In combination, a pair of cutting knives, one of which is movable with respect to the other and having cutting edges, one of said knives having a projecting finger in contact with the other knife to maintain said knives in proper relative position, and a lubricant saturated pad held against said knives at a point below the cutting contact of said knives.

In testimony whereof I affix my signature, in presence of two witnesses.

DUDLEY S. SEYMOUR.
